STOCKING

Emil F. P. Dost, Blackwood, N. J., assignor to Janedale Hosiery Mills, Inc., Philadelphia, Pa.,
a corporation of New Jersey

Application July 19, 1950, Serial No. 11,266

Term of patent 14 years

(Cl. D47—7)

To all whom it may concern:

Be it known that I, Emil F. P. Dost, a citizen of the United States, residing at Frankfort Avenue, Blackwood, Camden County, New Jersey, have invented a new, original, and ornamental Design for a Stocking, of which the following is a specification, reference being had to the accompanying drawings, forming part thereof.

Fig. 1 is a perspective view showing the novel stocking upon the leg of a wearer. The wearer is shown as standing on her toe.

Fig. 2 is a rear view of the same with a portion of the stocking intermediate at its ends being broken away in order to permit the showing of the portion carrying the novel design on as large a scale as possible.

Fig. 3 is a side view of the same with a portion of the stocking intermediate at its ends being broken away in order to permit the showing of the portion carrying the novel design on as large a scale as possible.

I claim:

The ornamental design for a stocking, substantially as shown and described.
